HEKTOGRAPH DEVICE

Bertha Herrmann, Minneapolis, Minn.

Application September 8, 1936, Serial No. 99,787

6 Claims. (Cl. 41—31.6)

My invention relates to hektograph devices and more particularly to devices of this kind in which sheet material is coated with a film of hektograph composition. An object of the invention is to provide sheet material having distinct advantages over such material as paper and cloth. I have discovered that sheet rubber like material possesses the following advantages for use as a base upon which to spread the hektograph composition: it is moisture proof even after considerable wrinkling or creasing; it has great tear-resistance; it has toughness combined with some "give" without undue elasticity; it has heat sealing qualities so that a moderate amount of heat with pressure makes possible an effective air tight seal at the edges. As an example, "Pliofilm" may be used. Another object is to provide a hektograph device consisting of sheet material of very considerable length which may be readily rolled up and from which pieces may from time to time be cut as needed for use.

The novel features which I believe to be characteristic of my invention are set forth with particularity in the appended claims. The invention itself, however, both as to its organization and method of operation, together with additional objects and advantages thereof will be best understood from the following description of specific embodiments when read in connection with the accompanying drawing in which,—

Fig. 1 is a perspective view of one form of my invention showing the sheet partly unrolled.

Fig. 2 is a perspective view of this form showing the sheet entirely rolled up and sealed from the air.

Fig. 3 is a perspective view similar to Fig. 2, but showing a different manner of sealing from the air.

Fig. 4 is a perspective view of another form of the invention.

Referring first particularly to Fig. 1, the numeral 10 designates a long sheet of rubber like material which is coated with a film 12 of hektograph composition. This figure shows the sheet in the form of a roll 14 from which a small section has been unrolled for immediate use and which may or may not be cut off. For convenience the roll 14 may be rolled up on a suitable core or rod 16. Fig. 2 shows the sheet material completely rolled up and also strips 18 of the rubber like material applied at the ends of the roll to make a good moisture and air seal. Fig. 3 shows an alternative construction in which the hektograph roll is covered with a small piece 20 of the rubber like material to which the hektograph composition has not been applied. Fig. 4 shows a modified form in which a comparatively short piece 22 of the rubber like material is coated with a film 24 of hektograph composition. To protect the hektograph sheet from the action of air and moisture, a protective sheet 26 is applied to the hektograph surface. The sheet 26 may consist of the rubber like material without the coating of hektograph composition.

The operation and advantages of my invention will be readily understood in connection with the foregoing description and the accompanying drawing. By placing a long sheet of the rubber like material coated with hektograph composition in the form of a roll, the hektograph device is in such form that it may be conveniently used for a considerable period of time. A suitable piece for immediate use is cut from the outer part of the roll and the rest of the roll is sealed up for future use. The pieces of hektograph material are used in a well known manner which it is not necessary to describe in detail. But the rubber like material has distinct advantages because it is moisture proof, has great tear-resistance, has toughness with some "give" without undue elasticity, and has heat sealing qualities so that a moderate amount of heat with pressure provides a good moisture and air seal.

Although I have shown and described specific embodiments of my invention, I am fully aware that other embodiments are possible. My invention, therefore, is not to be restricted except insofar as is necessitated by the prior art and by the spirit of the following claims.

I claim:

1. A hektograph device comprising a sheet of rubber like material which is moisture proof even after considerable wrinkling and creasing, which has great tear-resistance, which has toughness combined with some "give" without undue elasticity, and which has heat sealing qualities so that a moderate amount of heat with pressure makes possible an effective air tight seal at the edges, and a film of hektograph composition on the surface of said sheet.

2. A hektograph device comprising a long rolled up sheet of rubber like material which is moisture proof even after considerable wrinkling and creasing, which has great tear-resistance, which has toughness combined with some "give" without undue elasticity, and which has heat sealing qualities so that a moderate amount of heat with pressure makes possible an effective air tight seal at the edges, and a film of hektograph composition on the surface of said sheet.

3. A hektograph device comprising a sheet of rubber like material which is moisture proof even after considerable wrinkling and creasing, which has great tear-resistance, which has toughness 5 combined with some "give" without undue elasticity, and which has heat sealing qualities so that a moderate amount of heat with pressure makes possible an effective air tight seal at the edges, a film of hektograph composition on the 10 surface of said sheet, and an air and moisture proof protective covering therefor.

4. A hektograph device comprising a long rolled up sheet of rubber like material which is moisture proof even after considerable wrinkling 15 and creasing, which has great tear-resistance, which has toughness combined with some "give" without undue elasticity, and which has heat sealing qualities so that a moderate amount of heat with pressure makes possible an effective air tight seal at the edges, a film of hektograph composition on the 20 surface of said sheet, and an air and moisture proof protective covering therefor.

5. A hektograph device comprising a long rolled up sheet of rubber like material which is moisture proof even after considerable wrinkling and creasing, which has great tear-resistance, which has toughness combined with some "give" 5 without undue elasticity, and which has heat sealing qualities so that a moderate amount of heat with pressure makes possible an effective air tight seal at the edges, a film of hektograph composition on the surface of said sheet, and strips of 10 sealing material for the edges of the roll.

6. A hektograph device comprising a sheet of rubber like material which is moisture proof even after considerable wrinkling and creasing, which has great tear-resistance, which has toughness 15 combined with some "give" without undue elasticity, and which has heat sealing qualities so that a moderate amount of heat with pressure makes possible an effective air tight seal at the edges, a film of hektograph composition on the 20 surface of said sheet, and a protective covering therefor of the same material as said sheet.

BERTHA HERRMANN.
